UNITED STATES PATENT OFFICE.

HATTIE M. WRIGHT AND ELOISE REED, OF DES MOINES, IOWA.

DESIGN FOR A BOOTEE.

Application filed May 13, 1929. Serial No. 31,209. Term of patent 3½ years.

To all whom it may concern:

Be it known that we, HATTIE M. WRIGHT and ELOISE REED, citizens of the United States, residing in Des Moines, in the county of Polk, and State of Iowa, have invented a new, original, and ornamental design for Bootees, of which the following is a specification, reference being had to the accompanying drawings, forming a part thereof.

Fig. 1 is a top plan view of the bootee, and Fig. 2 is a side view of our bootee, showing our new design.

We claim:

The ornamental design for a bootee, as shown.

HATTIE M. WRIGHT.
ELOISE REED.
